CLAIM

We claim, the ornamental design for a locking device, as shown and described.

DESCRIPTION

FIG. 1 is a perspective view of a locking device, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is a perspective view of the locking device, shown in use with environment.

The broken lines depict portions of the article and environment that form no part of the claimed design.

1 Claim, 5 Drawing Sheets(56)
